CLAIM

The ornamental design for a three wheeled electric scooter, as shown and described.

DESCRIPTION

FIG. 1 is a perspective view of a three wheeled electric scooter showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings are for the purpose of illustrating portions of the three wheeled electric scooter that form no part of the claimed design.
